Primary Examiner — Cynthia Ramirez*(74) Attorney, Agent, or Firm* — Polson Intellectual Property Law, PC; Margaret Polson(57) CLAIM

The ornamental design for a cart, as shown and described.

DESCRIPTION

FIG. 1 is a front perspective view of our new design for a cart.

FIG. 2 is a side elevation view of the right and left sides, which are mirror images, of FIG. 1.

FIG. 3 is a front side elevation view of FIG. 1.

FIG. 4 is a top plan view of FIG. 1.

FIG. 5 is a bottom plan view of FIG. 1; and,

FIG. 6 is a back side elevation view of FIG. 1.

The features shown in broken lines are to show portions of the cart, which form no part of the claimed design.

1 Claim, 5 Drawing Sheets(56)
